UNITED STATES PATENT OFFICE.

FRANK T. JONES, OF BALTIMORE, MARYLAND, ASSIGNOR TO THE JONES SAFETY TRAIN CONTROL SYSTEM COMPANY, OF BALTIMORE, MARYLAND, A CORPORATION OF MARYLAND.

SAFETY TRAIN-CONTROL APPARATUS.

1,118,654.

Specification of Letters Patent. Patented Nov. 24, 1914.

Application filed March 22, 1913. Serial No. 756,085.

To all whom it may concern:

Be it known that I, FRANK T. JONES, a citizen of the United States, residing at Baltimore, in the State of Maryland, have invented certain new and useful Improvements in Safety Train-Control Apparatus, of which the following is a specification.

This invention relates to an improved safety train control apparatus.

10 The invention has particular reference to a controlling device similar to that set forth in U. S. Patents Numbers 1,010,371 and 1,010,372 granted November 28th, 1911.

One object of the present invention is to provide an improved arrangement of devices and circuits whereby one contact shoe may be utilized to coact with the caution ramp rails and also with the stop ramp rails and to give a signal of safety while traveling over said rails provided the track ahead is clear.

Another object is to provide an improved means whereby the contact may maintain a circuit on the vehicle that will prevent the operation of an air-brake or other valve during the time the vehicle is traveling between ramp rails and also while the shoe is passing a signal contact rail.

With these and other objects in view, the accompanying drawing illustrates in a diagrammatic way an application of the invention wherein,

Figure 1, shows the track rails of two blocks or sections; the signal and stop ramp rails with their local current supplies and the devices and circuits on the vehicle, and Figs. 2, 3, and 4 illustrate the three positions of the contact shoe.

Referring now to the drawing the numeral, 1, designates one of the track rails of a block or section on which the vehicle travels,—an insulation, 2, being provided to separate the rail of one block or section from the rail of the next adjoining block or section. Two ramp rails, 3, and, 4, are also provided preferably adjacent to the entrance to each block section,—the ramp rail, 3, being a caution-signal rail and the ramp rail, 4, being a stop rail. By referring to Figs. 1, 3 and 4 of the drawing it will be noted that the ramp rail, 3, has position in a horizontal plane below that in which the ramp rail, 4, is situated, and further,

that the rail, 3, is located at the exit end of a block or section while the rail, 4, is located at the entrance end of the next adjoining block. These latter locations however, while desirable, are not essential.

Each caution and stop ramp rail is normally, and during conditions of safety, connected to one side of a current supply.

In the present instance the caution ramp rail, 3, is shown connected by a wire, 5, and armature, 6, and wire, 7, to one side of a battery, 8. The stop rail, 4, has a wire connection, 9, which leads to an armature, 10, and a wire, 11, normally connects the armature with one side of a battery, 12. The other sides of batteries, 8, and, 12, are connected by wires, 13, and, 14, respectively, to the track rails, 1, but normally there is no connection between either ramp rail, 3, or, 4, and either rail, 1, so that the circuits are not normally completed from either battery, 8, or, 12, through either ramp rail, 3, or, 4.

An electro-magnet, 15, is so situated with respect to the armature, 6, as to normally attract the latter during periods of safety, so as to maintain the connection between the one side of battery, 8, and the caution ramp rail, 3, and said magnet, 15, is kept energized by means of a circuit through wires, 16, and, 17, which circuit includes a current supply from a clear block or section ahead as fully disclosed in said prior patented structures of November 28th, 1911. Another electro-magnet, 18, is provided to normally attract armature, 10, and maintain a connection from one side of a battery, 12, to stop ramp rail, 4, and a circuit is formed by wires, 19, and, 20, through said magnet, 18, which latter circuit includes a current supply also from a clear block or section ahead as is also fully set forth in said prior patents.

It will thus be understood that as long as the track ahead is clear both magnets, 15, and, 18, will be kept energized and the connections between one side of battery, 8, and the ramp rail, 3, and between one side of battery, 12, and ramp rail, 4, will be maintained. On the other hand if the track ahead is occupied both magnets, 15, and, 18, will become deenergized and the normal condition from one side of the battery, 8,

to ramp rail, 3, or the one side of battery, 12, and ramp rail, 4, will be broken to effect results which will presently be explained.

The vehicle is provided with a controlling device and in so far as the present invention is concerned the said controlling device may be an air-brake valve, a steam throttle valve or a current supply switch, therefore it is to be understood that when 10 using the expression controlling valve or controlling device it is to be construed as meaning any device that will shut off the power or apply the brakes.

In the present diagrammatic illustration 15 the controlling device, 21, has the form of a valve which is preferably located in the cab of the vehicle and said device has an arm, 22, which is normally held in such position as will permit the vehicle to advance unrestricted and under power, and will therefore be termed the running position. The vehicle also has a contact shoe, 23, which is sustained in such a way as to have a vertical or up-and-down movement and the shoe carries a contact bar or head, 24, which latter is insulated from the shoe although moved by the latter. The contact bar or head, 24, normally has position so as to engage two spaced contact plates, 25, and, 26, which are 20 also on the vehicle so as to close a circuit from one plate through the bar or head to the other plate. An electro-magnet, 27, is also carried on the vehicle as is also a current supply, like a battery, 28, and a wire or connection, 29, extends from one side of the current supply or battery to the said electro-magnet. Another wire, 30, extends from the electro-magnet to the contact plate, 26, on the vehicle while still another wire, 31, extends from the other contact plate, 25, to the other side of the battery.

From the foregoing explanation it will be understood that when the bar or head, 24, bridges across and connects contact plates, 25, and, 26, a circuit will be established from battery, 28, by wire, 29, to electro-magnet, 27; then by wire, 30, to contact, 26; then through bar on head, 24, to contact, 25, and by wire, 31, back to the battery. This circuit will be maintained as long as the bar or head, 24, closes across the gap between the contact plates, 25, and, 26, and consequently the electro-magnet, 27, will be kept energized during the maintenance of such circuit.

The function of the electro-magnet, 27, is to attract the arm, 22, of the controlling device and hold the latter in such a position as to keep the said device in the running position as long as the magnet is energized.

In addition to the normal running circuit above described the vehicle has wiring for substitute circuit which is entirely separate and independent of the normal running circuit and this substitute circuit wiring is

utilized during the periods that the contact shoe, 23, is in engagement with either of the caution or stop ramp rails, 3, or, 4. This substitute wiring includes a wire or other connection, 32, from the shoe, 23, to the electro-magnet, 27, and another connection or wire, 33, from the electro-magnet to the axle, 34, of the vehicle and from the axle to the wheel, 35, and then to track rail, 1.

It will thus be noted that the electro-magnet, 27, has two windings,—one of which receives a current from vehicle battery, 28, and the other which will receive a current from the local track battery, 8, as will presently be explained, and so long as current 75 from either of these sources of supply is passed through the electro-magnet the latter will be kept energized and the controlling device, 21, will be held in the running position. The substitute wiring on the vehicle 80 also includes a branch, 36, which extends from wire, 32, to a signal, such as a bell or lamp, 37, and from the latter a wire, 38, extends to and connects with wire, 33, so as to operate the signal as will presently be explained.

The operation of the invention is as follows:—During the normal running condition,—that is, when the track is clear, the vehicle will proceed, and at points between 85 the ramp rails the contact shoe will simply depend as illustrated in Fig. 2. During this period of travel (between ramp rails) the bar or head, 24, will form a connection between contacts, 25, and, 26, on the vehicle 90 and thus maintain a circuit from battery, 28, through electro-magnet, 27, to energize the latter and thus hold the controlling device, 21, in the running position. This condition prevails until the contact shoe reaches 105 a ramp rail, and the first ramp rail to be reached will be a caution rail, 3, which is shown in both Figs. 1 and 3 of the drawings. When the vehicle reaches a point where the contact shoe will rise up on the 110 caution rail, 3, and engage the latter, the upward movement of the shoe and the head, 24, will not be sufficient to carry the head from between the contact plates, 25, and, 26, consequently the electrical connection 115 from plate, 25, through the head, 24, to plate, 26, will be maintained and the normal running circuit from battery, 28, through electro-magnet, 27, will not be changed or broken while the shoe is on the caution 120 ramp-rail, 3. During the period that shoe, 23, engages and travels over the caution ramp rail, 3, however, a circuit additional to the normal running circuit, will be formed to give a signal indicating that the 125 track is clear, provided, of course, that safety conditions exist ahead. This safety signal, 37, is located in the cab of the vehicle and may be a bell or other device. To actuate this signal the contact shoe, 23, 130

and the wheel, 35, will effect a completion of the circuit from the local caution-rail battery, 8,—the circuit being from one side of the battery, 8, by wire, 7, to armature, 6, 5 and wire, 5, to caution ramp-rail, 3; then by shoe, 23, and wires, 32, and, 36, to signal, 37, then return by wires, 38, and, 33, to axle, 34, and wheel, 35, then to rail, 1, and wire, 13, back to the local signal battery, 8. 10 From the foregoing it will be seen that when the contact shoe engages a caution ramp rail, not only will the normal circuit on the vehicle be maintained but if the track is clear, current from local battery, 8, will be picked up from the ramp rail, 3, and 15 conducted through the signal, 37, so as to advise the operator that the road is clear. If on the other hand the track ahead is not clear the electro-magnet, 15, will become de- 20 energized and allow armature, 6, to drop thus cutting off the connection between the ramp rail, 3, and one side of battery, 8, so that no current can be picked up by the shoe from said caution ramp rail, conse- 25 quently the signal on the vehicle will not operate to indicate a clear track because of the lack of current in the ramp rail and the failure to get a clear signal will warn the operator to go cautiously and cut down 30 speed. Whether the track ahead is clear or not however, the normal circuit on the vehicle from battery, 28, to electro-magnet, 27, will be maintained during the travel of the shoe, 23, over the caution ramp rail because 35 the height of the said caution ramp rail is not sufficient to raise the head or bar, 24, entirely above the contacts, 25, and, 26. After the above leaves the caution ramp rail, 3, it will return to its normal lowered position, as shown in Fig. 2, and will remain in 40 this latter position until the stop ramp rail, 4, is reached. If now, the track ahead is clear and the shoe rides up onto the stop ramp rail, 4, as shown in Fig. 4, the normal running circuit on the vehicle will be broken because the shoe will be elevated sufficiently to move the head or bar, 24, entirely out of contact with plates, 25, and, 26, but simultaneously with the said upward movement, 45 the shoe will complete a substitute circuit through the electro-magnet, 27, on the vehicle from the local stop rail battery, 12, and by this means keep the magnet, 27, energized and keep the controlling device in 50 the running position. This substitute circuit is completed as follows: From one side of local battery, 12, by wire, 11, to armature, 10, and wire, 9, to stop ramp rail, 4; then through shoe, 23, which latter at that time 55 will be on the stop ramp rail to wire, 32, then through electro-magnet, 27, to energize the latter and keep the controlling device in the running position then return by wire, 33, axle, 34, wheel, 35, to rail, 1, and by 60 wire, 14, back to the other side of battery, 65

12. When completing this substitute circuit through the stop ramp rail the road must be clear and I again utilize the branch, 26, signal, 37, and wire, 38, to give a clear signal while the shoe is passing over the 70 stop rail. On the other hand if the track ahead is occupied or unsafe the electro-magnet, 18, in the local track circuit will be de-energized and by releasing the armature, 10, 75 will break the connection from the one side of battery, 12, to stop ramp rail, 4, consequently the shoe, 23, would not pick up a current from the stop ramp rail but would break the normal vehicle circuit thus de-energizing magnet, 27, and allowing arm, 80 22, to drop so as to move the controlling device, 21, to the stop position.

From the foregoing explanations it will be seen that but one shoe is utilized to engage both caution and stop ramp rails; 85 that the shoe in operation may be moved to one of three positions, to-wit: full down while traveling between ramp rails; partially up when traveling over a caution ramp rail and full up when traveling over 90 a stop ramp rail; that in two positions the normal running circuit on the vehicle will be maintained; that in two positions when the road is clear a clear signal will be indicated; that in one (full up) position a 95 substitute current will be picked up from the stop ramp rail, provided the road is clear, and that this latter circuit is entirely separate and independent of the normal running circuit on the vehicle because of the 100 double winding of the vehicle magnet, 27.

Having thus described my invention what I claim and desire to secure by Letters Patent is:—

1. The combination with the track rail, of 105 a caution ramp rail; a stop ramp rail; a current supply having one side normally connected to the caution ramp rail; a second current supply having one side normally connected to the stop ramp rail; a vehicle having 110 a controlling device; an electro-magnet and a circuit including a third current supply and shunt electro-magnet; a contact shoe also on the vehicle; a signal device on the vehicle; means for establishing a circuit from the 115 first-named current supply through the signal when the contact shoe passes over a caution ramp rail; means actuated by the contact shoe for interrupting the circuit of the said third current supply through the said 120 electro-magnet when the contact shoe engages the stop ramp rail and means for establishing a circuit from the second current supply and stop ramp rail through the said electro-magnet on the vehicle when the track 125 ahead is clear and while the contact shoe is passing over the stop ramp rail.

2. The combination with the track rail, of a 130 caution ramp rail; a current supply having one side connected to the caution ramp rail;

a stop ramp rail higher than the caution ramp rail; a second current supply having one side connected to said stop ramp rail; a vehicle having a controlling device; an electro-magnet for controlling said device; a circuit on the vehicle and including a third current supply and said electro magnet; a contact shoe on the vehicle; means actuated by the contact shoe for normally 10 maintaining the circuit from the third current supply through the electro-magnet said means also maintaining said circuit while the shoe is in engagement with the caution signal rail; a signal device on the vehicle; 15 means for establishing a circuit from the current supply of the caution ramp rail through the signal while the shoe is on the

caution ramp rail; means whereby the movement of the shoe onto the higher ramp rail will interrupt the circuit on the vehicle from the said third current supply through the electro-magnet and means for substituting a current from the said second current supply and stop ramp rail through the electro-magnet to keep the latter energized during periods of safety while the shoe is in engagement with the stop ramp-rail. 20 25

In testimony whereof I affix my signature in presence of two witnesses.

FRANK T. JONES.
